Carter Carburetor Corporation, St. Louis, Mo.,
a corporation of Delaware

Application December 10, 1942, Serial No. 468,564

13 Claims. (Cl. 123—127)

This invention relates to internal combustion engines and particularly to automotive engines of the multi-cylinder type. The invention is, in some respects, an improvement of the invention shown in my earlier filed application, Serial No. 453,116, filed July 31, 1942. In devices of the character shown in the previous application, the fuel is cut off from some or all of the cylinders in accordance with the power requirements of the engine as indicated by the vacuum in the intake manifold. The fuel cut off is accomplished by a vacuum control valve in the fuel passage. Where the carburetor is of the plain tube type having a fuel system comprising a plurality of outlets receiving fuel from a single inlet, the most convenient place for the cut-off valve is at the fuel inlet. This is particularly true in cases where the invention is to be applied in the field to an engine which is already equipped with a carburetor, and where the only changes which can conveniently be made are those which involve nothing more than the addition or substitution of parts without the necessity for doing any drilling or other machine work on the carburetor or engine. Where the fuel is cut off at the inlet of the branched fuel passage, there necessarily remains a small quantity of fuel in the passage posterior to the valve. After the valve is shut off, the application of suction to the idle passage in the normal operation of the engine drains the fuel systems posterior to the cut-off valve, thus wasting a small quantity of gasoline. Of course, the quantity in the fuel passages may be very small, but the operation is repeated so often as to involve noticeable waste of fuel over a period of time.

While the loss of fuel in the manner above described might be disregarded, a slight lag in acceleration may occur, due to the fact that when the throttle is open, it is necessary to refill the fuel system before any discharge can be had into the mixing conduit. The cut-off valve is instantly opened on account of the loss of vacuum as soon as the throttle is opened, but it takes a noticeable amount of time for the suction of the carburetor to refill the fuel passages. This lag in acceleration may be substantially eliminated by withdrawing the fuel from the passages when the valve is cut off and returning it to refill the passages when the engine is again accelerated.

It is an object of my invention to prevent the waste of the fuel contained in the fuel system posterior to the cut-off valve.

It is a further object of my invention to prevent the lag in acceleration caused by the neces-

sity of refilling the fuel passages posterior to the cut-off valve.

It is a further object of my invention to produce an engine and carburetor combination capable of smoothly varying the number of cylinders which are in operation in accordance with the amount of power required by the engine at any given moment.

It is a further object of the invention to produce a new and generally improved device of the class described.

The invention will be better understood upon reference to the following description and accompanying drawings, referring to which:

Figure 1 is a diagrammatic view of a multi-cylinder internal combustion engine having my invention applied thereto.

Figure 2 is a sectional elevation showing a carburetor equipped for the performance of my invention.

Figure 3 is a diagrammatic sectional view taken along the line 3—3 of Figure 2.

Figure 4 is an elevation of the device shown in Figures 2 and 3 with parts broken away and others shown in section along the line 4—4 of Figure 2.

Figure 5 is a detail assembly view showing one of the metering rods or control valves together with its operating means and connections.

Figure 6 is a detail view showing the coasting spring.

Figure 1 shows a multi-cylinder internal combustion engine having eight cylinders numbered 1 to 8. The engine block is indicated generally by the reference character 9, and this is connected to intake manifolds 10 and 11 which are served with fuel mixture by a carburetor 12 having two barrels 13 and 14. Each barrel of the carburetor is supplied with fuel from the float chamber 15 by means of separate fuel passages 16 and 17, and the fuel supply to each passage is controlled by metering rods or valves 18 and 19, respectively.

Main jets 20 and 21 are provided with restricted orifices forming valve seats to receive the cooperating valve portions of the metering rods under certain conditions hereafter described.

It will be understood that the barrels of the carburetor may be substantially the same in construction, and each comprises an air inlet 22, one or more venturis 23, a main fuel nozzle 24, an idle fuel nozzle 25, and a throttle valve 26, which is mounted on shaft 27 controlling the fuel discharge outlet 28. The carburetor is bolted onto the intake manifolds by means of the flange 29.

An idling adjustment screw 30 is provided for controlling the discharge outlet of one of the idling passages. The idle passages are supplied with fuel from the jets 20 and 21 through passages 31, which are connected to the passages 16 and 17, respectively, at a point between the main jet and the discharge outlet of the main jet. It will be understood that the idle fuel may be supplied independently from the main jets, if desired, as shown in my prior Patent No. 1,967,708, issued June 5, 1934. Since the present construction is intended for application in the field, as well as for original equipment, I have shown an existing type of carburetor which is provided with idle passages, discharge ports, and adjusting screws for both barrels of the carburetor. In order to apply the invention, one of the idling screws 30 is removed and replaced by the pipe fitting 301 and the connecting passage 302 between the low speed nozzle 25, and the lower branch of the low speed nozzle 251 is closed by a plug. Since the engine uses both idling passages only during starting and warming up, the lower branch of the idle passage is not really required, because the excess fuel is sufficiently supplied by reason of the fact that the choke is partly closed. In this manner, I am able to obtain a suction connection for operating the fuel snatcher without the necessity of drilling holes in the carburetor or manifold.

The above construction is fairly well known (except as indicated), and is frequently referred to as the plain tube type of carburetor. The construction is such that when the throttle valve is in nearly closed position, only fuel from the idle ports 25 is delivered to the engine, and when the throttle is opened, the fuel discharge is transferred to the main nozzle 24, and the suction from the main nozzle prevents the discharge of fuel at the outlet 25, it being understood that the venturis 23 cause a higher suction to be established at the outlet of the main nozzle than that which exists at 25 during open throttle operation.

The metering rods 18 and 19 are connected to a pin 32 which is mounted on piston rod 33. This rod is connected to the piston 34 mounted in cylinder 35 for operation by suction through the passage 36. This suction passage is connected to the discharge outlet of the carburetor posterior to the throttle, as at 31. A spring 38 is mounted under the piston in a position to be compressed when the suction is high, so as to draw the members 18 and 19 down into the main jets. The metering rod 18 is provided with a valve portion 39, which seats in the main jet 20, to cut off all fuel supply to the carburetor barrel 13 and the inside manifold 10 when the suction is high. The point at which this main jet is cut off may be at a suction corresponding to 5" to 10" of mercury, depending on the particular installation, and at low suctions the fuel is permitted to flow normally, subject to regulation by the graduated metering portion 40 carried at the lower end of the rod 18. In some installations, I replace the main jet with one slightly smaller and omit the graduated portion 40, so that the member 39 merely acts as a valve to control the jet which is either open or closed and not regulated.

The rod 18 is connected with the pin 32 by means of a limited, lost motion, flexible connection 41 which may be provided with a light spring 42 to insure the firm seating of the valve 39 without preventing further downward movement of the rods 33 and 19. The rod 19 is provided

with a valve portion 43 similar to the valve 39, which may be seated to shut off the fuel from the main jet 21 by further downward movement of the piston 34 after the valve 39 has seated. The spring 38 is calibrated to permit the seating of the valve 43 when the suction exceeds the normal idling suction, for instance, when coasting at speeds higher than the normal idling speed of the engine.

One of the important features of this device is the provision of means for preventing the valves 39 and 43 from occupying a position in which they substantially restrict but do not completely close the jet, and I have provided special means for this purpose, as follows:

A magnet 54 is mounted on the rod in such a position that its lower end approaches contact with the top of the jet just at the time when the valve reaches closing position. The jet is made 20 of magnetic material, so that the magnet holds the jet firmly to the seat although with a very light pressure. The spring 42 is a very light spring, just sufficient to hold the weight of the rod and valve against the slight suction normally 25 present which draws the metering rod portion 40 of the valve downwardly, but as soon as the magnet approaches the jet, the additional force of the magnet causes the valve to close with a snap action, which is only overcome when some substantial force is applied by the spring 38 or by 30 the manually operated member 49. However, as soon as the valve is broken away from its seat, the magnetic action is weakened, and the valve opens with a snap action. This arrangement 35 prevents the valve occupying a position in which it would allow a highly restricted flow of fuel through the jet but still not sufficient to permit operation of the cylinders. If the valve remained in such nearly closed position, it would simply 40 result in the wastage of fuel.

Another means for preventing the valve from occupying a nearly closed position is the action of the suction itself. During normal operation, with the valve open, the normal suction of the 45 carburetor can act on the metering rod portion 40 only, but the diameter and area of this portion are small compared to the diameter and area of the valve member 39. Thus, when the valve member begins to restrict the flow, the 50 downward force exerted on it is increased in the measure of the difference in area between the rod portion 40 and the valve member 39, and this constitutes the snap action means for closing or 55 opening the valve regardless of the magnet 54. In both cases, the spring 42 may be used to give a highly flexible action to the valve, although this action is limited by the length of the slot 41, so that the valve may be positively closed or 60 opened.

In many installations, the action of the spring 38 may be used alone to oppose the suction action and position the metering rods and the valves 39 and 43. However, in some installations, the positive opening and closing of the 65 valves will be improved by the use of the precompressed spring 55, which is held in a capsule composed of top and bottom washers 56 held together by the rivet 57 which limits the expansion of the precompressed spring 55, but does not prevent compression. The use of the spring 55 permits comparatively rapid downward movement of the metering rod after the establishment of a predetermined suction. Also, the action of this capsule is to present a fairly solid bottom for the 70 piston 34 during the normal idling period.

The valve 39 is designed to shut off its jet at approximately 10 inches of mercury of vacuum alone, while the valve 43 is not intended to shut off its jet until a vacuum of at least 18 inches of mercury is developed. With this wide difference required in the action of the valves, it would be necessary to provide for substantial travel of the piston 34 and corresponding extra length of the metering rod portions 40, if the spring 38 alone were depended on to control the actuation of the valves. The provision of the spring capsule 56 permits the piston 34 to reach a definite limit of travel responsive to any vacuum between 10 inches and 18 inches of mercury. This position is retained until the 18 inches is exceeded, at which point the spring 55 yields and permits closing of the valve 43.

By this construction, the action of the parts may be more accurately controlled, and the size and length of the parts may be reduced. It will be understood that the figures of 10 inches and 18 inches of mercury are only illustrative and may be varied substantially according to the requirements of the particular engine and the use to which the device is applied. Without making any attempt to list the factors on which the closing pressures of the valves will depend, it may be noted that the compression ratio of the engine is an important factor in determining the normal idling manifold vacuum.

It will be understood that the usual accelerating pump is provided, and that the pump discharge to the inside carburetor 13 is made a little heavier than to the outside carburetor, because the manifold 10 will most frequently become dry and will require more fuel to wet it upon acceleration. The outside manifold is longer and has more surface to wet, but the wetting action is initiated sooner after coasting, and is kept wet during normal idling.

It will also be understood that the fuel may be first shut off in the outside manifold 11 while permitting the engine to idle on the inside manifold 10, but, in most constructions, the shut off of the fuel to the inside manifold would be preferred on the ground that the manifold is shorter, has less wet surface and capacity and, therefore, requires less time and fuel to set it in operation after idling.

The throttle shaft 27 is normally biased to close the throttle by the conventional spring which is not shown. The shaft 27 is connected by means of the lever 44, link 45, and lever 46 to the rock shaft 47. This rock shaft carries a lever 48 having a projecting arm 49 which is constructed and arranged to contact the underside of the horizontal projection 50 which is preferably integral with the upper end of the piston rod 33. The member 50 has upturned lugs 51 (Figure 3) on which the pin 32 is mounted, so as to make a direct operating connection between the piston 34 and the metering rods 18 and 19. This connection, however, is flexible by reason of the fact that the spring 42 is bent at its ends to pass through the openings 52 which are controlled through the metering rod above and below the slot or lost motion connection 41. The connection between the throttle valve and projecting arm 49 is such that the projection 50 and the metering rods are forced upwardly upon an opening movement of the throttle, and, in the preferred construction, the rod 19 is first lifted off its seat to initiate the supply of fuel to the outside manifold 11, and the rod 18 is forced off

its seat later in the opening movement of the throttle.

It will be understood that the usual accelerating pump actuated by opening movement of the throttle is provided. An example of this pump may be found in my previous patent above mentioned, but it is not believed necessary to describe it in detail. A conventional automatic choke mechanism is also provided, but this is not essential to the present invention and need not be described.

While the automatic choke mechanism is not described in detail, reference may be had to Coffey Patent No. 2,085,351, issued June 29, 1937, or Blattner Patent No. 2,166,899, issued July 18, 1939, which shows means for preventing the closing of the throttle to its full idle position by the throttle spring, which is provided to normally maintain it in that position. This means 18 operates during warming up period, so that the starting and warming up is accomplished by joint action of all the cylinders of the engine, and it should be noted that the adjustment of the arm 50 with respect to the member 49 is such as 20 to prevent the closing of the valve 39 when the fast idle is in operation; that is to say, when the throttle is held in the fast idle position, as by 25 means corresponding to the members 35-41-26 of the Coffey patent, or 32, etc., of Blattner, the 30 throttle is opened far enough to insure the lifting of the valve 39 off of its seat. It may also be noted that when the engine is equipped with an 35 automatic starting device corresponding to that which is shown in Coffey Patent No. 2,174,313, 40 issued September 26, 1939, the opening of the 45 throttle by means of the accelerator pedal will be sufficient to lift the valve 39 off its seat before the starter switch is operated. It may also be noted generally that the link 126 shown in Figure 2 of this application corresponds generally to the link 26 of Coffey 2,085,351, and to link 32 of Blattner, and the housing 142 and thermostatic control mechanism may be said to correspond generally to the housing 42 and thermo-control mechanism 45 of the Coffey patent.

From the foregoing, it will be observed that the present invention may be adopted in carburetors of various types, particularly where the fuel distributing system includes a manifold so constructed and arranged as to feed the explosive mixture to separate banks of cylinders from a carburetor mechanism. In such assemblies, it will be practical with the present invention to permit the idling of a motor only with an extremely small amount of power such as may be derived from an idling mixture supplied to only a part of the total number of cylinders of the engine. This development is elastic, at least to the extent that one or more jets can be totally closed where only a limited amount of power may be necessary to drive along a substantially level road at a relatively limited speed. The closing of a jet, or of more than one jet, is essentially synchronized with the mechanism controlling the normal operation of the engine, and it is preferable that the closing of the jet or jets be brought about with a snap action such as will tend to eliminate undesirable and irregular explosions tending to bring about a possible surging condition in the motor.

The greater part of the above subject matter is disclosed in my copending application, Serial No. 453,116, filed July 31, 1942. I have found that the construction can be further improved by the provision of means for withdrawing the fuel from

the fuel passages of the carburetor between the cut-off valve and the discharge outlet. This fuel withdrawing means is preferably constructed and arranged to operate by suction, so as to withdraw the fuel at the time the fuel supply is cut off and to return it as soon as the fuel supply valve is again opened.

A convenient means for applying this invention to a carburetor in the field is embodied in the structure shown in Figure 3. The idling screw of the barrel of the carburetor, to which the fuel supply is controlled by the valve 39, is removed and replaced by the pipe fitting 301, and a plug is placed in the passage 302, so that the full manifold suction is applied to the pipe fitting. From this fitting, the suction is conveyed through a pipe 303 to a connecting member 304 at the end of cylinder 305, which contains a double piston 306 normally held in the position shown by the spring 307. The travel of the piston is adjustable by means of the screw 308 which is held in adjustable position by lock nut 309. The cylinder 305 is threaded, as at 310, to screw into the opening at the base of the main nozzle 24 at the bottom of the fuel well 311.

The piston 306 is constructed and arranged to respond to the same vacuum at which the valve 39 closes, so that simultaneously with the closing of the valve, the piston is withdrawn against the spring 307. Since the connection 310 is at the bottom of the fuel well, it quickly withdraws the fuel from the well 311, the main nozzle 24, and the chamber 16. This prevents the discharge of the fuel from these passages through the port 25, which would otherwise occur as soon as the valve 39 is closed, it being noted that the upper part of the well 311 is provided with the air passage 312, and also other air bleeds above the fuel level would permit the discharge of the fuel contained in the passages, even after the valve 39 is closed. Upon acceleration of the engine, the fuel which has been withdrawn into the cylinder 305 is immediately replaced, due to the return of the piston 306.

In order to obtain the greatest possible speed in the resumption of normal functioning by the nozzle 24 when fuel feeding is resumed after being cut off I provide a restricted passage 320 in the connection 310 between the nozzle base or well 11-311 and the upper end of the cylinder 305. This passage is axially aligned with the passageway through the nozzle 24 in such a manner as to direct a jet of fuel up through the nozzle base so as to produce an injector action to assist in refilling the nozzle and restarting the fuel flow therethrough. The action of this jet may continue from one to five seconds so that there is a continuous tendency to produce flow through the nozzle whenever the suction drops sufficiently to permit the spring 307 to shift the piston 306 to the position shown in Fig. 3.

It might be supposed that leaving the outlet of the snatcher pump wide open and unrestricted would result in a quicker refilling of the nozzle, but tests show that the cylinders supplied by the nozzle 24 resume operation more quickly and smoothly when the restricted passageway 320, together with its injector action, are used instead of an unrestricted passage at 320. This may be due in part to better synchronization between the action of the valve 39 and the action of the piston 306, but it has been found that the restriction and injector action are still desirable even when the valves 39 and piston 306 are interconnected so as to positively insure simultaneous operation.

Details of structure in which the valve 39 or its equivalent is interconnected with the piston 306 are shown in copending application Serial No. 453,116, filed July 31, 1942.

I claim:

1. In an internal combustion engine, passage means for liquid fuel supply, valve means controlled in accordance with the power demand on the engine for cutting off said passage means, means for withdrawing fuel from the passage means when said valve means is closed, and means for restoring said fuel to the passage means when said valve means is again opened.

2. In an internal combustion engine having an intake manifold, a carburetor for supplying fuel to said manifold, said carburetor having a fuel passage, a valve for controlling said fuel passage, means responsive to manifold vacuum for controlling said valve, and means connected to said passage at a point posterior to said valve for withdrawing fuel when said valve is cut off.

3. In an internal combustion engine having an intake manifold, a carburetor for supplying fuel to said manifold, said carburetor having a fuel passage, a valve for controlling said fuel passage, means responsive to manifold vacuum for controlling said valve, means connected to said passage at a point posterior to said valve for withdrawing fuel when said valve is cut off, and means for restoring said fuel to said passage when the valve is again opened.

4. In an internal combustion engine having an intake manifold, a carburetor for supplying fuel to said manifold, said carburetor having a fuel passage, a valve for controlling said fuel passage, means responsive to manifold vacuum for controlling said valve, means connected to said passage at a point posterior to said valve for withdrawing fuel when said valve is cut off, and means for delivering said fuel to the fuel supply system of the engine when said valve is again opened.

5. In an internal combustion engine having an intake passage, a carburetor, a throttle for controlling the flow of mixture from said carburetor to said engine, said carburetor having a fuel passageway, valve means for controlling said fuel passageway, means connected to said fuel passageway posterior to the valve for withdrawing fuel therefrom, and means operated by the manifold vacuum for controlling said valve and said fuel withdrawing means.

6. In an internal combustion engine having an intake passage, a carburetor, a throttle for controlling the flow of mixture from said carburetor to said engine, said carburetor having a fuel passageway, valve means for controlling said fuel passageway, means connected to said fuel passageway posterior to the valve for withdrawing fuel therefrom, means operated by the manifold vacuum for controlling said valve and said fuel withdrawing means, and means controlled by said throttle for overriding said vacuum controlled means.

7. In a multi-cylinder internal combustion engine, separate intake conduits leading to separate cylinders of the engine, fuel supply means for said intake conduits, valve means for cutting off the supply of fuel from one of said fuel supply means, means connected to said fuel supply means at a point posterior to said valve for withdrawing fuel therefrom when the valve is cut off, said means being constructed and arranged to return the fuel thereto when said valve is again opened.

8. In a multi-cylinder internal combustion engine, separate intake conduits leading to separate cylinders of the engine, fuel supply means for said intake conduits, valve means for cutting off the supply of fuel from one of said fuel supply means, means connected to said fuel supply means at a point posterior to said valve for withdrawing fuel therefrom when the valve is cut off, said means being constructed and arranged to return the fuel thereto when said valve is again opened, and means controlled by the vacuum in one of said intake conduits for controlling said valve.

9. In a multi-cylinder internal combustion engine, separate intake conduits leading to separate cylinders of the engine, fuel supply means for said intake conduits, valve means for cutting off the supply of fuel from one of said fuel supply means, means connected to said fuel supply means at a point posterior to said valve for withdrawing fuel therefrom when the valve is cut off, said means being constructed and arranged to return the fuel thereto when said valve is again opened, means controlled by the vacuum in one of said intake conduits for controlling said valve, and manual means for overriding said vacuum means.

10. In a fuel supply device for internal combustion engines, means forming a mixing conduit, means forming a fuel supply chamber, a passage leading from said fuel supply chamber to said mixing conduit, an expansible chamber connected to said passage, means forming a movable wall for said expansible chamber, said movable wall having positions corresponding to complete expansion and complete contraction of said chamber, valve means for controlling the flow of fuel through said passage, means responsive to an operating condition of said engine for shifting said valve, and means shifting said wall to its chamber expanding position under conditions which result in a shift of said valve to closed position.

11. In a fuel supply device for internal combustion engines, means forming a mixing conduit, means forming a fuel supply chamber, a passage for conveying fuel from said fuel supply chamber to said mixing conduit, snap action valve means for opening and closing said passage to cut off or reestablish flow of fuel therethrough, and auxiliary means synchronized with said valve action for assisting the reestablishment of fuel flow through said passage when said valve is opened.
12. In a fuel supply device for internal combustion engines, means forming a mixing conduit, means forming a fuel supply chamber, a passage for conveying fuel from said fuel supply chamber to said mixing conduit, snap action valve means for opening and closing said passage to cut off or reestablish flow of fuel therethrough, auxiliary means synchronized with said valve action for assisting the reestablishment of fuel flow through said passage when said valve is opened and for assisting the abrupt termination of fuel flow through said passage when said valve is closed.
13. In an internal combustion engine, a mixture conduit, a fuel reservoir adjacent said conduit, a main fuel passage extending upwardly at an angle from the lower part of said reservoir into said conduit, a metering orifice element in said passage, a cylinder projecting from the bottom of said reservoir in line with said passage and communicating with said passage posterior to said orifice element, a piston in said cylinder, spring means normally holding said piston at the upper end of said cylinder, and a vacuum connection from the lower end of said cylinder to said conduit, said cylinder and piston being constructed and arranged to withdraw fuel from said fuel passage when high suction exists in said conduit and to return said fuel when the suction drops in said conduit.

GEORGE R. ERICSON.
